DRY CLEANING APPARATUS AND FLUID CIRCULATING SYSTEM THEREFOR

Louis Angelus, New York, and Daniel Lawrence Baylis, Bellrose, N. Y.; said Baylis assignor to said Angelus

Application April 12, 1935, Serial No. 15,986

1 Claim. (Cl. 210—62)

Our present invention relates generally to cleaning apparatus, and has particular reference to an apparatus intended for the so-called "dry cleaning" of garments and the like.

5 One of the main objects of our invention is to provide a unitary and compact apparatus and fluid circulating system, whereby a fixed quantity of cleaning fluid may be employed and reemployed over a period of time, except for such 10 minor additional amounts of fluid as may be required, occasionally, to make up for losses.

When garments are immersed in a cleaning fluid, the fluid becomes contaminated with impurities. In order for the fluid to be capable of 15 efficient reuse, these impurities must be removed. A simple mechanical filtering action will serve to eliminate certain of the impurities, but this alone is insufficient because there are types of impurities, such as greases, which pass right through a mechanical filter.

20 Cleaning fluid being relatively expensive, it is unfeasible to discard it entirely, and, therefore, many attempts have been made in the past to purify the same by various means. Sometimes, the fluid is subjected to a distilling operation, 25 whereby greases and the like, boiling at a higher temperature than the fluid, are separated out. Other methods involve the use of alkalis or other chemicals for the purpose of saponifying or otherwise capturing the greases and suspended impurities and permitting the clarified fluid to be 30 decanted.

It is one of the principal objects of the present invention to provide an apparatus which is 35 so compact that it may be feasibly installed in relatively small establishments. Systems involving distillation, saponification, or other similar treatments of the fluid are much too cumbersome and expensive for an apparatus of this 40 type. Accordingly, it is a characterizing feature of the present invention to provide an arrangement whereby the cleaning fluid may be efficiently and continuously purified and clarified by a means different from those hereinbefore alluded 45 to.

More specifically, it is a feature of our invention to harness the phenomenon of adsorption to our present purpose, by subjecting the cleaning fluid, in a unique manner, to an adsorptive 50 material, such as fuller's earth.

One of the features of our present system resides in the employment of a porous bag or its equivalent, the bag having a layer or deposit of adsorptive material lining its inside surface, and 55 a closed circulatory system forcing the cleaning

fluid continuously into and through the bag. This results in subjecting the fluid to the action of the adsorptive lining, whereby those impurities which have escaped removal by an ordinary mechanical filter are separated from the fluid by virtue of the fact that the adsorptive material has a greater affinity for them than the fluid itself has. 5

Periodically, of course, the adsorptive material must be replaced, and it is a further feature of 10 our invention to provide a means in the circulatory system for permitting the introduction into the system at intervals of a predetermined fresh charge of the adsorptive material. More particularly, we provide a novel arrangement of 15 chamber in the circulatory system, the chamber being adapted to accommodate a frangible cartridge containing a measured charge of the material, whereby the continuous circulation of the fluid causes the latter to pick up the adsorptive 20 material, carrying it into the porous bag, and depositing the same in the form of the layer desired on the inside surface of the bag. 25

Another important feature of our invention lies in the means whereby the fluid is subjected, also, 30 to a pure mechanical filtering action. In one embodiment, a mechanical filter of the pressure type is arranged in series with the aforementioned bag. In another embodiment, the porous bag upon which the adsorptive lining is formed is 35 itself capable of fulfilling a mechanical filtering action. 40

The present invention is applicable to apparatuses and systems of the so-called "batch" type, or the so-called "continuous" type. Where the 35 invention is applied to "batch" cleaning, it is a further feature of our invention to permit selected quantities of the purified fluid to be withdrawn from and returned to the circulatory system without impairing the continuous circulation 40 through the mechanical filter and the adsorptive material. 45

As a direct result of the features of our invention, as hereinbefore illustratively specified, a fixed quantity of cleaning fluid may be repeatedly used and reused in an apparatus of such 50 utter simplicity that the present type of installation may be deemed to be entirely different in kind from the ordinary cumbersome and expensive installations which have heretofore sought to accomplish the same general objective. 55

We achieve the foregoing objects, and such other objects as may hereinafter appear or be pointed out, in the manner illustratively exemplified in the accompanying drawing, wherein— 55

Figure 1 is a diagrammatic view of a circulatory system and apparatus embodying the features of our present invention;

Figure 2 is a diagrammatic view of a modification of the invention;

Figure 3 is an elevational cross-sectional view through the chamber forming part of the circulatory system; and

Figure 4 is an enlarged fragmentary cross-sectional view through a porous bag of the present character.

In the apparatus and system of Figure 1, which is the type of installation employed for so-called "batch" cleaning, a suitable reservoir tank or chamber 10 has one or more porous bags 11 mounted therein. The detailed structure of each bag forms no part of our present invention, but it has been found feasible to make each bag substantially cylindrical in cross-section with one end secured, as at 12, to a supporting ring or framework which has a communication to a conduit 13. Where a plurality of bags are used, they may be conveniently mounted in association with a header or manifold 14 interposed between the conduit 13, on the one hand, and the plurality of bags, on the other.

Leading from the chamber 10 is a conduit 15 which leads into the conduits 16 and 17, preferably through the intermediary of a two-way valve 18. The valve is of a character which permits either the conduit 15 or the conduit 17 to be placed into communication with the conduit 16, but never both together.

A suitable pump 19 is mounted in the conduit 16 and is adapted to pump the fluid continuously into the outlet conduit 20. In the latter, a two-way valve 21 permits a connection to be established, at will, with either the conduit 22 or the conduit 23. The latter conduit leads into the special chamber 24 (presently to be described in greater detail); and the outlet from the chamber 24 leads into the conduit 13 hereinbefore referred to.

For a purpose hereinafter to be explained, a relatively small bleeding conduit or by-pass 25 establishes a continuous direct connection between the conduits 20 and 13.

The conduit 22 leads, as indicated in the drawing, to a suitable cleaning drum or chamber or a plurality of such devices, where the actual dry cleaning process is to be carried out; and, similarly, the conduit 17 leads from the cleaning drum or drums. Since these drums or chambers form no direct part of the present invention, they have not been shown in the drawing.

Before describing the operation of our present system, reference will be had to Figure 3, in which the present special chamber 24 is more clearly depicted. This chamber is preferably cylindrical in shape; is composed of suitable metal; and is provided with an inlet 26 and an outlet 27, whereby the fluid from the conduit 23 is directed into the chamber 24 and thence outwardly into the conduit 13.

A removable cover 27 is provided on the chamber 24, and any suitable clamping means may be arranged to permit this cover to be securely clamped into position, or opened, as may be desired.

In accordance with our invention, there is mounted in the bottom wall of the chamber 24, in alignment with the outlet 27, a stiletto-like, perforated projection 28. The perforations are designated by the reference numeral 29, and the projection may be conveniently provided in the

form of a separate element having the collar 30 and the threaded portion 31, the latter being screwed into engagement with the outlet neck 27.

The chamber 24 is adapted to accommodate a measured charge of suitable adsorptive material, and our invention contemplates the accommodation of such a charge within a frangible container 32, which may be made, for example, of tin or the like. The container 32, containing the charge 33 of adsorptive material, is adapted to fit snugly within the chamber 24, and is provided with a removable cover (not shown). When a charge is to be inserted into the circulating system, the cover 27 is removed; the container 32 is impaled downwardly over the projection 28; the upper cover of the container 32 is then removed and discarded; and the cover 27 is then replaced. The flow of fluid into the chamber 24 is thereby constrained to pass through the charge 33, picking up the adsorptive material, and thence through the perforations 29 and into the conduit 13. This leads, in turn, to the bag or bags 11, and as a result, a deposit 34 of adsorptive material presently forms upon the inside surface of the bag or bags 11, as indicated in Figure 4.

The operation of the apparatus and system of Figure 1 is as follows.

The operator arranges first that the valves 18 and 21 seal off the conduits 17 and 22. He then starts the pump 19, and this establishes a continuous flow of cleaning fluid through the chamber 24, into and through the bag or bags 11, and thence through the pump 19. Assuming that the operator has freshly loaded the chamber 24 with a charge of adsorptive material, there is presently deposited on the inner surface of the bag or bags 11 a layer 34 of adsorptive material. The fluid is constrained to pass into and through the bag or bags 11, thus compelling it to pass outwardly through the layer 34. Any impurities in the fluid, of the character which are adapted to be adsorbed, are picked up and held by the layer 34. More solid impurities are subjected to a mechanical filtration action during the passage through the bag or bags 11. As a result, the fluid drawn out of the conduit 15 and forced by the pump into the conduit 20 is substantially purified.

When a cleaning operation is to be performed, the operator turns the valve 21 so as to cause the fluid in the conduit 20 to pass into the conduit 22 and thence into the cleaning drum. During this operation, the continuous circulation of the fluid through the adsorptive material remains unimpaired, because of the by-pass 25. After the desired quantity of fluid is in the cleaning drum or drums, the valve 21 is manipulated to re-establish the normal connection between the conduits 20 and 23.

The cleaning operation having been completed, the valve 18 is manipulated to establish a connection between the conduits 17 and 16, whereby the contaminated fluid from the cleaning drum is drawn back into the circulatory system; and when all the fluid has been returned, the valve 18 is restored to its normal position, connecting conduits 15 and 16. It will be observed that the continuous circulation through the adsorptive material is still unimpaired and uninterrupted.

The operator can then immediately repeat the procedure, if he so desires, because the fluid that is drawn out of the conduit 15 is always of a purified character, having been constrained to pass through the adsorptive material and also through the filter constituted of the bag or bags 11.

Periodically, it is necessary to clean or replace the bag or bags 11, and this is preferably accomplished at the time that a fresh charge of adsorptive material is loaded into the chamber 24.

5 During this process, the fluid may be conveniently pumped through the conduit 22, into one or more cleaning drums, where it can be temporarily accommodated or stored until the replacement of the bag and loading of the chamber 24

10 has been accomplished.

In Figure 2, we have shown the manner in which the present invention is applicable to a so-called "continuous" system of cleaning. In this case, the conduit 35 leads from the cleaning 15 drum or drums to the pump 36, and is thence directed through the mechanical filter 37, then into the chamber 24, and then into and through the bag or bags 11. The latter is mounted in a compartment or tank 38 from which a conduit

20 39 leads back to the cleaning drum or drums.

In the system of Figure 2, the fluid, as before, is subjected continuously to a mechanical filtering action and also to a passage through a porous bag having a lining of adsorptive material. 25 The chamber 24 is of the character illustrated in Figure 3, and may be charged and recharged, as hereinbefore described. The bag 11 is of the character illustrated in Figure 4.

Where the system is continuous, as in Figure 30 2, the separate mechanical filter 37 is preferable because of the added filtering capacity that is required. (Also, because of the separate filter 37 (which may be of any suitable character, preferably of the so-called "pressure type"), it is usually

35 satisfactory to employ only a single bag 11.)

While our invention is not restricted to any specific type of adsorptive material, nor to any specific cleaning fluid, we will mention that the fluid may be of any well-recognized type, such as 40 synthetic, chlorinated hydrocarbons, petroleum base cleaning solvents, benzine, Stoddard solution, or the like. The adsorptive material is a suitable mixture of fuller's earth or other clay, charcoal or the like, and kieselguhr. These ingredients are suitably chosen and intermixed to provide for the removal of pigmentation from the fluid, for the withdrawal of colorless oils which would cause rancidity, and for the general removal or adsorption of such impurities as would 45 otherwise remain unaffected by a mechanical filtering action. The mixture should be of such a constituency that it will not clog the pores of the porous bag in which the lining is formed.

It will thus be seen that we have provided an 50 apparatus and fluid circulating system of uniquely efficient character. Not only is the complete installation of unusually compact and relatively inexpensive type, but the operation of the system is entirely practical and of great sim-

plicity. A given quantity of cleaning fluid may be repeatedly used; the garments that are cleaned are capable of subjection always to a purified and uncontaminated fluid; and at very small expense, and without any special skill or cumbersome installation, the operator is enabled periodically to replenish the means which effects the continuous clarification of the fluid.

One of the outstanding advantages which characterizes our present system, distinguishing it 10 from those which have heretofore been attempted, arises from the fact that the present cleaning fluid is never permitted to become so contaminated that its purification becomes a matter of difficulty. It is characteristic of most cleaning 15 fluids that, where impurities are allowed to accumulate in ever-increasing amounts, the difficulty of thereupon removing them becomes disproportionately great. By the present system, whether the same be applied to a batch apparatus or a continuous apparatus, the fluid is always subjected to an immediate purification which prevents any building up of undue contamination. In the batch system, for example, whatever batch of fluid has been used for a cleaning 20 operation is immediately returned to the closed circulatory system, where it is subjected at once to the purification action and merges, once again, with the balance of the fluid which has been continuously undergoing the purification process. 25 Accordingly, the operator is enabled at any time to withdraw from the system a selected quantity of fluid, with the assurance that the fluid is more than adequately pure for cleaning purposes.

It is to be understood that the details herein 30 described and illustrated, for the purpose of explaining the nature of our invention, may be made by those skilled in the art without departing from the spirit and scope of the invention as expressed in the appended claims. It is, therefore, intended 35 that these details be interpreted as illustrative, and not in a limiting sense.

Having thus described our invention, and illustrated its use, what we claim as new and desire to secure by Letters Patent is—

In a dry cleaning apparatus, a porous bag, a closed circulatory system whereby a quantity of cleaning fluid is continuously forced into and through said bag, a layer of adsorptive material lining the inside of said bag, a cartridge having 40 an openable top and a frangible bottom and containing a measured charge of said material, a chamber in the circulatory system adapted to accommodate said cartridge, and means associated with said chamber for puncturing the frangible bottom of said cartridge during its insertion thereinto.

LOUIS ANGELUS.
DANIEL L. BAYLIS.
